MAIN VALVE FOR WELL TESTING TOOLS

Mordica O. Johnston, Glendale, Calif.

Application April 25, 1936, Serial No. 76,464

3 Claims. (Cl. 166—1)

This invention relates to oil well tools, and particularly pertains to a valve for a testing tool and the like.

In the operation of oil well testing tools of the type shown in my co-pending application entitled Well testing method and apparatus therefor, filed by me on the 19th day of May, 1934, Serial No. 726,583, which has matured into Patent No. 2,073,107, granted March 9, 1937, a well packer is provided to seal off the column of fluid standing in the well from an area of the well to be tested. This packer and a testing tool upon which it is mounted are carried by a string of pipe by which the assembled structure is lowered into the well and manipulated. It is common practice to lower the testing tool and the string of pipe into the well with the string of pipe empty so that a sample of formation fluid from below the packer may be entrapped within the testing tool and the string of pipe. Testing tools of this type usually embody a valve structure through which fluid from the formation is admitted into the drill string after the packer is set and by which the formation sample may be entrapped. In practice it has been found that due to the abrasive action of the fluids which pass through the valve and are entrapped thereby the valves may be cut out, often resulting in causing the parts of the testing tool and the valve structure to separate so that a part of the tool with the packer may be lost in the hole. It is the principal object of the present invention to provide a valve structure for the purpose and of type here set forth in which the valve elements will remain in their assembled position irrespective of any damage which may occur due to the abrasive action of fluids acting upon the valve and thereby insuring that the elements of the testing tool and the valve structure will be maintained in an assembled condition so that the packer and the testing tool can be withdrawn from the well bore.

The present invention contemplates the provision of a valve structure preferably of the tappet type, the valve and seat of which have relative vertical movement, the valve structure being otherwise provided with limiting means whereby the valve elements may be retained in an assembled condition, irrespective of whether or not the valve tappet and its seat are abraded or worn to an extent which would otherwise cause them to become separated and disassembled.

The invention is illustrated by way of example in the accompanying drawing in which:

Figure 1 is a view in elevation showing an oil well testing tool with parts broken away to disclose the valve structure.

Fig. 2 is an enlarged view in longitudinal sec-

tion showing various parts of the valve structure with which the present invention is concerned.

Fig. 3 is a view in transverse section through the valve structure as shown on the line 3—3 of Fig. 2.

Fig. 4 is a view in transverse section as seen on the line 4—4 of Fig. 2.

Fig. 5 is a view in transverse section through the valve structure as seen on the line 5—5 of Fig. 2.

Referring more particularly to the drawing 10 indicates a drill string to which is attached a testing tool comprising an upper section 11, and a lower section 12. Disposed beneath the section 12 is an equalizing valve section 13 carrying a 15 well packer 14 at its lower end. The sections 11 and 12 are connected by a tubular mandrel 15 which extends downwardly and is formed with a reduced cylindrical portion 16 upon which splines 17 are formed. Another reduced cylindrical portion 18 extends downwardly as a continuation of the mandrel and carries a valve head 19 at its lower end. The entire mandrel is formed with a central longitudinal bore 20 threaded at its lower end to receive the threaded shank 21 of the valve head 19. Directly below the threaded shank 21 of the valve head is a cylindrical portion 22 of larger diameter than the threaded portion, thus forming a shoulder 23 which abuts against the lower end face of the tubular mandrel 15. An enlarged tapered valve shoulder 23 is formed as a part of the valve head 19 and is of a diameter greater than the outside diameter of the portion 18 of the mandrel 15. The valve head 19 is formed with an outwardly beveled seat 24 which rests when seated against a valve seat 25 which is carried at the lower end of a valve bushing 26. The inside diameter of the valve bushing 26 agrees substantially with the outside diameter of the portion 18 of the mandrel 15 so that the mandrel 15 may have a sliding fit through the bushing as it moves the valve face 24 toward and away from the valve seat 25. The valve bushing 26 is threaded into the lower end of the longitudinal bore 21 formed as a part of a tubular valve sleeve 28. The upper end of the valve sleeve 28 is formed with a plurality of longitudinal slots 29 within which the splines 17 on the mandrel may slide as the valve sleeve 28 and the mandrel have longitudinal movement with relation to each other. The diameter of the bore 27 at the upper end of the sleeve 28 is substantially equal to the diameter of the upper portion of the mandrel so that the mandrel will be properly guided within the sleeve. The upper end of the sleeve 28 is reduced in diameter to receive an adjusting nut 30 which is threaded into position thereon. This nut has a central opening 31 through it substantially agreeing in diameter with that of the upper

end of the mandrel 15. Attention is directed to the fact that this diameter is smaller than the overall diameter of the circle which describes the outer arcuate ends of the splines 17. Thus 5 in the event of relative longitudinal movement between the mandrel 15 and the sleeve 28 with its nut 30 it will be evident that the mandrel could not be pulled upwardly and outwardly through the nut but would be limited in its movement therewith to insure that it will remain in assembled relation thereto irrespective of whether or not the valve head 19 is abraded away to such an extent that the mandrel could be drawn upwardly and out of the valve sleeve 28. 10 Disposed above the nut 30 and interposed between it and the lower end of the element 11 is an expansion spring 32 which tends to hold the valve face 24 of head 19 against the valve seat 25 at all times. Valve ports 33 are formed 15 in the cylindrical portion 22 of the valve head 19. In operation of the present invention the structure is assembled as shown in Figs. 1 and 2 of the drawing. In this position it will be seen that the splines 17 are within the keyways 29 so that the 20 mandrel 15 may have longitudinal movement relative to the valve sleeve 28 while preventing the mandrel from having rotational movement with relation to the valve sleeve 28. The spring 32 maintains the tapered valve face 24 of the 25 valve head 19 in seated relation to the valve seat 25 and in this position valve ports 33 will be sealed off from the passageway within a lower barrel structure 34 which is threaded on to the lower end of the valve sleeve 28 and forms a part 30 of the unit 12. When relative telescoping action takes place between the valve sleeve 28 and the mandrel 15 the valve head 19 will move away from its seat 25. This will establish communication between the barrel 34 and the interior 35 passageway 20 of the mandrel through the valve ports 33. In the event that an unexpected surge of fluid occurs before the valve can be closed it often happens that the velocity and the pressure of the fluid flowing through the valve 40 ports 33 will be sufficient to cause the valve head and its shoulder 23 to be eroded away, or so weakened that when a lifting action is produced on the mandrel 15 the head 19 will break off or will pull through the bushing 28 and thus 45 release the mandrel from the valve sleeve 28 and parts carried thereby. In the present instance, however, this cannot take place, since an upward pull on the mandrel will bring the upper ends of the splines into engagement with the 50 end face of the nut 30. This will insure that the sleeve 28 will hang on the mandrel so that the sleeve with its associated parts may be withdrawn from the well bore and will not be lost in the hole to require an expensive fishing job. 55 It will thus be seen that the valve structure here disclosed, while simple in operation, provides safety features which insure that its parts will not become disassembled in the event of damage to the tool, and while it is being withdrawn from the hole. 60

While I have shown the preferred form of my invention, as now known to me, it will be understood that various changes might be made in the combination, construction, and arrangement 65 of parts, by those skilled in the art, without departing from the spirit of the invention as claimed.

Having thus described my invention, what I claim and desire to secure by Letters Patent is:

1. A device of the character described, a valve sleeve adapted for attachment to a packer, a mandrel longitudinally slidable in said sleeve and adapted for attachment to a drill string, means interlocking said mandrel and said sleeve for positive rotation in unison while permitting relative longitudinal movement therebetween, a bushing having threaded engagement with said sleeve and providing a valve seat, a valve head carried by said mandrel and adapted to rest upon said valve seat whereby upward movement of said mandrel will be limited, and cooperating means carried by said valve sleeve and said mandrel for holding said parts in assembled relation if said valve seat does not limit the upward movement of said valve head. 10

2. Valve means for oil well testers and the like, comprising a valve sleeve adapted to be connected with a well packer having a passageway therethrough communicating with a passageway extending through said valve sleeve, a valve bushing detachably connected to said sleeve and having a valve seat provided thereon, a mandrel extending through said sleeve and adapted to have longitudinal movement relative thereto, said mandrel and said sleeve being splined together, said mandrel being formed with a central passage, a valve head carried at the lower end of said mandrel and adapted to seat against said valve seat to prevent a flow of fluid through said seat, said valve head being adapted to close the lower end of said mandrel passage and having openings whereby when said valve head is off of said bushing seat fluid may flow through said seat and into said mandrel, a nut threaded on the upper end of said sleeve and through which said mandrel extends, said nut overhanging the end of said sleeve to stand in an obstructing position relative to the splines on said mandrel whereby said mandrel and said sleeve will be retained in an assembled position, if said valve head has no engagement with said valve seat. 30

3. A valve for oil well testers and the like comprising a valve sleeve adapted to be connected to a well packer having a passage therethrough to communicate with a passage through said valve sleeve, a bushing including a valve seat detachably secured at the lower end of said valve sleeve, a mandrel extending through said valve sleeve and adapted to have longitudinal movement relative thereto, said mandrel and said sleeve being splined together, said mandrel having a passageway extending therethrough, a valve head carried at the lower end of said mandrel and adapted to seat against said valve seat to prevent a flow of fluid through said valve seat, said valve head being adapted to close the lower end of said passageway through said mandrel and having ports whereby when said valve head is off of said valve seat fluid may flow into 40

said mandrel, a nut threaded on the upper end of said valve sleeve and through which the upper end of said mandrel extends, said nut overhanging the end of said valve sleeve to stand in an obstructing position relative to said splines on said mandrel whereby said mandrel and said sleeve will be retained in assembled position, an abutment at the upper end of said mandrel, and a spring interposed between said abutment and said nut, and acting to hold said valve head on its seat. 50
